MECHANISM FOR USE IN APPLYING PRESSURE TO SHOE BOTTOMS

Francis J. Better, Beverly, Mass., assignor to
United Shoe Machinery Corporation, Paterson,
N. J., a corporation of New Jersey

Application August 2, 1933, Serial No. 683,353
Renewed October 24, 1934

13 Claims. (Cl. 12—33)

This invention relates to improvements in machines for applying pressure to shoe bottoms and is illustrated herein as embodied in a machine for cement attaching soles as, for example, in the manufacture of compo shoes.

It is an object of the invention to provide improved means for positioning a shoe and sole relatively to each other, for example as a preliminary to the application of sole attaching or sole laying pressure.

In accordance with the foregoing a feature of the invention comprises an improved pad box structure including means movable into position over a pad for applying pressure to a sole and shoe positioned on the pad, a pair of sole positioning fingers or gages, and a separate pair of shoe positioning gages, both pairs of gages being carried by a bracket mounted on the pad box with which the gages are to cooperate and arranged for heightwise adjustment relatively thereto. As illustrated herein and in accordance with another feature of the invention the fingers or gages are supported on the bracket by means of a slide arranged for adjustment lengthwise of the pad box, said gages being arranged to pivot on the slide about an axis extending transversely of the pad box. By this arrangement the gages may be adjusted heightwise for operating on shoes having different heel heights and may also be adjusted lengthwise to accommodate shoes of different sizes.

In accordance with still another feature of the invention the sole and shoe gages of the illustrated construction are operated by movement of the pressure applying means into operative position over the pad thereby insuring that the sole and shoe will be positioned relatively to each other on the pad before the application of sole attaching pressure.

With the above and other objects and features in view the invention will now be described with reference to the accompanying drawings and pointed out in the claims.

In the drawings,

Fig. 1 is a plan view of the heel portion of a pad box embodying my invention and including gage mechanism for positioning the heel end portions of a shoe and sole relatively to each other on the pad;

Fig. 2 is a longitudinal sectional view of the gage mechanism of Fig. 1 taken substantially on the line II—II of Fig. 1 and showing adjacent portions of the pad box in elevation;

Fig. 3 is a sectional view of the gage mecha-

nism on the line III—III of Fig. 1, on a smaller scale than Fig. 1;

Fig. 4 is an elevational view of a pad box embodying my invention, looking toward the heel end of a shoe on the pad, and illustrating also parts of mechanism for applying pressure to a shoe and sole on a pad;

Fig. 5 is a perspective view partly in section showing particularly the gage fingers for positioning the heel end portion of a sole upon the pad, together with portions of the operating mechanism for those fingers and for the corresponding shoe positioning fingers;

Fig. 6 is a perspective view on a smaller scale of the end portion of a pad box provided with the gage mechanism of the present invention and illustrating also some of the connections for operating said mechanism;

Fig. 7 is an exploded view on a larger scale of means for adjusting one set of gage fingers relatively to the other set;

Fig. 8 is a view of a portion of the gage operating mechanism, shown also in Figs. 4 and 6, but on an enlarged scale; and

Fig. 9 illustrates a portion of the operating connections for the sole positioning gages.

My invention is illustrated herein as embodied in a cement sole attaching machine of the type disclosed in an application for Letters Patent of the United States Serial No. 636,202, filed October 4, 1932, in the name of Milton H. Ballard et al. Accordingly, the pad box B is shown as carried by the forwardly projecting portion of a shelf or bracket 16 (Fig. 4) which projects radially of the rotary turret of the machine. The right-hand end (as viewed in Fig. 2) of the pad box B is provided with vertical guideways in which a slide 17 carrying an outwardly extending bracket 18 is mounted for vertical sliding movement, the slide 17 and bracket 18 being maintained in their uppermost positions when the pad box is idle by a pair of compression springs 19 housed in the slide 17 and supported at their lower ends by a second bracket 20 which is secured by bolts 22 to the end of the pad box B. The shank of a screw 23, threaded through a lug 25 formed on the slide 17 and held in adjusted position by a set-screw 27 (Figs. 4 and 6), passes loosely through the lower part of the bracket 20 whereby the head of the screw 23, by engagement with the bracket 20, limits the upward movement of the slide 17 under the influence of the springs 19. Therefore, the screw 23 serves as an adjustable stop. The bracket 20 has a rearwardly extending portion 24 which serves to support the fulcrum 26 of a bell crank

lever 28 which forms part of the mechanism for operating the heel end gages now to be described.

The pad box B is provided with mechanism for positioning the heel end of a sole and shoe on the pad, such mechanism being spring actuated under control of the bell crank lever 28. This mechanism comprises a pair of sole engaging fingers 150, 151 (best shown in Figs. 1 and 5) and a pair of shoe engaging fingers 152, 153, the two fingers 10 of the respective pairs being connected by intermeshing gearing 154, 156, as shown in Figs. 3 and 5. These two sets of fingers are carried by a group of three approximately horizontal castings 160, 200, 202 secured one upon another by cap screws 15, 204, the casting 160 being pivoted at 162 to a support 164 mounted for sliding movement lengthwise of the pad on the bracket 18 and held in adjusted position by a hand screw 166 passing through a slot 168 in the bracket 18 and threaded into the casting 164. The castings 160, 200, 202 are normally held in adjusted position with respect to the pivot 162 by the cooperation of an adjustable stop screw 170 (Fig. 2) and a compression spring 172, which latter tends to rock the casting 160 in a 25 counterclockwise direction, as viewed in Fig. 2, the adjustment being such as to provide a small clearance between the end portions of the sole engaging fingers 150, 151 and a plate or shelf 165 secured to the upper end of the slide 17 and underlying and supporting the extreme end portion of the sole of a shoe operatively positioned on the pad, as shown in Fig. 2. The adjustment lengthwise of the pad provided by the screw and slot 166, 168, together with the spring-controlled rocking movement about the pivot 162 and the spring-controlled heightwise movement of the bracket 18 resulting from its mounting on the springs 19 permit the casting 160 to be effectively positioned as 35 may be necessary or desirable in accordance with the varying characteristics of different shoes which are to be operated upon.

When the sole attaching pressure is applied the sole of the shoe sinks somewhat into the pad P, causing downward movement of the slide 17 and the bracket 18, by reason of the engagement of the plate 165 with the sole of the shoe, this movement being permitted by compression of the springs 19. Thus the carrier 160, 200, 202, and the gage fingers 150, 151, 152, 153, move downwardly so that the 45 relation of the shoe and sole to the gages is not disturbed. If, however, the sole engaging face of the pad should be deformed in such a manner as to prevent downward movement of the sole engaging fingers 150, 151 to the same extent as the downward movement of the sole of the shoe, then the carrier 160, 200, 202 will rock in a clockwise direction, as viewed in Fig. 2, about its pivot 162, thereby compressing the spring 172 which, however, will return the carrier to its normal position 50 with the stop screw 170 in engagement with the slide 164 when the sole attaching pressure is released.

The sole engaging fingers 150, 151 are pivoted at 158, 159 to the casting 200, as shown in Fig. 3. 55 An extension of the finger 151 carries beneath its lower surface a roll 174 (Figs. 3 and 5) located in an inclined cam slot 176 formed in a slide member 178 mounted for forward and rearward movement, that is movement substantially toward and 60 from the operator and, therefore, widthwise or transversely of the pad box. Thus movement of the slide 178 will rock the fingers 150, 151 about their pivots. For this purpose a compression spring 180 is housed in the lower portion of the casting 160, bearing at one end against that cast- 70

ing and at the other end against the slide 178 so that it tends to move the slide 178 rearwardly, thereby swinging the sole engaging ends of the fingers 150, 151 toward each other into engagement with a sole (indicated at S in broken lines in Fig. 1). When the pad P is at rest and idle at the operating station, however, the spring 180 is held under compression with the slide 178 in its forward position so that the fingers 150, 151 are positioned with their sole engaging ends separated 10 and inoperative. The slide 178 is moved to that position by means of a roll 182 mounted upon the end of the bell crank lever 28, the other arm of which is connected by a link 184 to the end of the upwardly extending arm of a bell crank lever 15 304 (Figs. 1 and 9). Thus, when the treadle 300, which is connected to the lever 324, is depressed, the roll 182 is withdrawn to the position shown in Fig. 1 and the sole engaging ends of the fingers 150, 151 are moved toward each other 20 and into engagement with the sole S by the spring 180. Later in the operation of the machine, after the shoe and sole have been positioned upon the pad P, the roll 182 is moved forwardly, positively engaging the slide 178 and forcing it forwardly so that the gage fingers 150, 151 are moved 25 out of engagement with the sole.

The shoe engaging fingers 152, 153 are located approximately above the sole engaging fingers 150, 151, and like the latter are provided with 30 interengaging gear segments to maintain the fingers properly centralized. These shoe engaging fingers are pivoted at 190, 191 to a slide 192 normally secured to the casting 200 by a friction clamp including an adjusting lever 196 by the adjustment of which (as hereinafter more fully described) the line with respect to which the shoe engaging fingers 152, 153 are centralized may be adjusted transversely of the pad relatively to the line with respect to which the sole engaging 40 fingers 150, 151 are centralized so as to compensate for the unsymmetrical shape of the heel portion of a shoe whenever such may be necessary.

The shoe engaging finger 153 is provided on its upper surface with a roll 208 (Fig. 3) located in a cam slot 210 formed in a slide member 212 mounted for forward and rearward movement in the casting 202. The slide 212 carries an upstanding bracket 214 to which is secured by a ball and socket joint a link 216 extending rearwardly (as shown in Figs. 1, 4 and 6) and pivoted at 218 (Fig. 4) to an arm 220 which in turn is pivoted at 222 to a forwardly and rearwardly swinging frame member 224 forming a part of the machine disclosed in said application Serial No. 636,202 and which, when the pressure is to be applied to a shoe and sole on the pad, is swung forward manually, to the left as viewed in Fig. 4, by means of a handle 226 grasped by the operator. When a shoe is being held under pressure on the pad P the arm 220 occupies the position illustrated in Fig. 4. When, however, a pad reaches the station at which the pressure is released, the upper end of the frame member 224 swings rearwardly (to the right in Fig. 4) and the arm 220 is latched to the frame member 224, as illustrated in Fig. 8. For this purpose a latch lever 230 is pivoted at 232 to the frame member 224, being urged in a counter-clockwise direction, as viewed in Figs. 4 and 8, by a tension spring 234 anchored at one end to an end of the latch lever 230 and at the other end to the frame member 224, as shown in Fig. 4. The other end of the 75

latch lever 230 is provided with an angular detent 236, preferably a hardened metal block, arranged to be received in a notch 238 formed in a lug 240 projecting from the arm 220. An adjustable screw 227, threaded through a projection on the latch lever and arranged to engage the frame member 224, serves to limit counter-clockwise movement of the latch lever relatively to the frame member. Thus, when the arm 224 is moved forwardly with the latch in the condition shown in Fig. 8, the shoe engaging fingers 152, 153 move toward each other until they reach the shoe which has been positioned on the sole S and centralize it with respect to the sole. After this the resistance to further forward movement of the rod 216 is sufficient to force the notch 238 rearwardly over the end of the detent 236, releasing the latch mechanism (as shown in Fig. 4) and permitting the frame 224 to be pulled forward if necessary without causing the fingers 152, 153 to exert undue pressure on the shoe.

After the latch mechanism is released and the rod 216 is disconnected from the frame member 224, the shoe engaging fingers 152, 153 are held against the shoe only by the position of the slide 212. While the fingers cannot be forced away from the shoe owing to the angle of inclination of the slot 210 in which the roll 208 is located (this angle being such that the fingers are locked against opening movement), nevertheless, if there should be some slight displacement of the shoe relatively to the sole, for example, if the shoe should move forwardly a bit before the pressure is actually applied, the frame member cannot move the slide farther forwardly to bring the fingers again into engagement with the shoe. In order, therefore, to keep the shoe positioning fingers bearing against the shoe even if some slight movement of the shoe takes place after the latch mechanism is released but before pressure is applied to the shoe, a tension spring 250 (Figs. 2 and 4) is provided, one end of which is secured to the inner end of the slide 212 and the other end to the casting 202. The action of the spring 250 is to urge the slide 212 forwardly or toward the operator and thus tend to hold both fingers against the sides of the shoe.

The shoe engaging fingers are withdrawn from the shoe, after it has been centralized with respect to the sole and the latch released, in the following manner. When the pad reaches that station of the machine just in advance of the operating station the pressure on the shoe and sole is released, thus allowing the frame member 224 to be swung out of position over the shoe and moved rearwardly into inoperative position, this being effected by mechanism fully described in the Ballard application previously referred to. As the frame member swings rearwardly into inoperative position the tension spring 250 operates to hold the slide member 212 forwardly so that the fingers 152, 153 will be held against the shoe to cause the arm 220 on the frame member to be moved forwardly from the position shown in Fig. 4 until the notch 238 is engaged by the detent 236 on the latch lever 230, thus connecting the slide member 212 again to the frame member 224. Further rearward movement of the frame member carries the slide 212 rearwardly against the tension of the spring 250 and moves the gages 152, 153 away from the shoe into their open or inoperative position.

It should be understood, of course, that the frame 224 is provided with suitable abutments,

one of which is indicated at A in Fig. 4, for engaging the shoe and last and that these abutments are forced downwardly to apply sole attaching pressure by mechanism which may be of the character disclosed in said application Serial No. 636,202.

The mechanism for adjusting the slide 192 relatively to the casting 200 is best shown in the exploded view of Fig. 7. As shown in that view the slide 192 is provided with a T-shaped slot 400. The casting 200 is provided with a slot 402 underlying the bar of the T slot 400 and somewhat greater in length than the bar of the T slot. A block 404 is secured to the casting 200 by a screw-and-slot connection 406 which is used primarily as a setting up adjustment. The block 404 is provided with a tapered hole 408 serving as a seat for a hub 410 formed on the adjusting lever 196. A crank pin 412 projects from the hub 410 into the upright 414 of the T slot 400 so that when the lever 196 is rocked the slide 192 will be moved lengthwise relatively to the casting 200. In order to prevent the lever 196 from escaping, the shank of a screw 416 passes through a hole bored in the hub 410 and through the slot 402, being provided at its lower end with a nut 418 bearing against a plate 419 (Fig. 3) underlying the casting 200. To provide suitable friction so that the slide 192 will remain in adjusted position a spring 420 surrounding the shank of the screw 416 is housed in the hub 410, the lower end of the spring bearing against a flange formed at the bottom of the hub 410 and the upper end of the spring bearing against a washer 422 underlying the head of the screw 416. By means of this construction it will be seen that the friction between the slide 192 and the casting 200 may be adjusted by turning the screw 416 further or not so far through the nut 418, thereby compressing the spring 420 to a greater or less extent.

It now remains to describe the mechanism for controlling the sole gages 150, 151. For this purpose the bell crank lever 28, counter-clockwise movement of which (as viewed in Fig. 1) permits the compression spring 180 to move the sole positioning gage members 150, 151 into operative position, is operated, when the pad is at the operating station of the machine, by the depression of the foot treadle 300 (Fig. 9). As already pointed out, the left-hand end of the link 184 is connected at 302 to the upper end of the bell crank lever 304. This lever 304 is fulcrumed at 306 to a suitable part of the rotating frame of the machine. A tension spring 308, anchored at 310 to the upper standing arm of the bell crank lever 304 and at 312 to the frame of the machine, urges the bell crank lever 304 in a clockwise direction, as viewed in Fig. 9, until an adjustable stop 314 carried by the lever 304 engages a stationary abutment 316. Thus the spring 308 tends to retract the roll 182 from engagement with the slide 178.

A rod 320 extends upwardly from the treadle 300 forwardly of the fulcrum of the treadle and is pivoted at 322 to a lever 324 which is fulcrumed at 326 to a stationary cam track 328 adjacent to the operating station of the machine and in close proximity to the path of movement of the approximately horizontal arm 329 of the bell crank lever 304 as the pad moves into and from the operating station. A roll 330 carried by the arm 329 of the bell crank lever 304 rides along the cam track 328 as the pad reaches the operating station, rocking the lever 304 in a counter-clockwise direction, as viewed in Fig. 9 and thereby rocking the bell crank lever 28 in a clockwise direction, as

viewed in Fig 1, to move the slide 178 forwardly thereby separating the sole engaging fingers 150, 151 and moving them from operative position. A movable cam track section 332 carried by the lever 324 forms a continuation of the cam track 328 and is so positioned that the turret of the machine comes to rest with the roll 330 of the appropriate bell crank lever 304 upon the cam track section 332. With the parts in this position, the bell crank lever 304 has been rocked in a counter-clockwise direction from the position shown in Fig. 9 so that the roll 182 carried by the bell crank lever 28 has been moved to force the slide 178 forwardly and withdraw the sole engaging fingers 150, 151. After the shoe previously operated on has been removed and a suitably prepared sole has been placed upon the pad with its heel portion between the gage fingers 150, 151, the operator depresses the treadle 300 thereby moving the cam track section 324 downwardly. This permits the lever 304 to rock in a clockwise direction to the position shown in Fig. 9 under the tension of the spring 388, thereby rocking the bell crank lever 28 in a counter-clockwise direction to permit the spring 180 to expand thus urging the sole engaging fingers 150, 151 into engagement with the sole on the pad. In order that it will not be necessary for the operator to retain his foot upon the treadle 300, a latch lever 338 is fulcrumed at 340 to the cam track 328. The latch lever 338 is provided with a shoulder 342 engaging a hardened steel plate 344 secured to the lever 324 and is urged in a counter-clockwise direction, as viewed in Fig. 9, by a tension spring 346. Thus when the treadle 300 is depressed the latch lever 338 is moved by the spring 346 until its shoulder 342 snaps past the end of the block 344, thereby latching the lever 324 in the position shown in Fig. 9. The operator may now remove his foot from the treadle 300.

After a shoe has been positioned upon the sole on the pad and the sole-attaching pressure applied, the turret rotating mechanism is operated, as disclosed in said application Serial No. 636,202, filed October 4, 1932, in the name of Ballard et al., and the bell crank lever 304 moves to the right as viewed in Fig. 9. In order to release the latch 342, thereby permitting the lever 324 to rise, a cam roll 350 is carried by the bell crank lever 304, the axis of the roll 350 coinciding with the axis about which the bell crank lever 304 is fulcrumed. The upper side of the lever 324 has formed thereon, at its right-hand portion, as viewed in Fig. 9, a convex cam surface which is inclined upwardly for about half its length and then extends downwardly to the end of the lever. As the roll 350 moves to the right it first engages this cam surface on the lever 324, depressing that lever slightly so as to relieve the pressure of the block 344 against the latch shoulder 342 after which the roll 350, without releasing the lever 324, contacts with an upwardly extending cam surface 352 formed on a finger extending to the right from the latch lever 338 thereby rocking the latter in a clockwise direction against the tension of the spring 346 to unlatch it from the block 344 and, since the roll 350 has not yet passed out of engagement with the cam surface on the lever 324, permitting this lever to rise gradually under the influence of a treadle spring 368.

The lower end of the rod 320 is surrounded by a compression spring 360 bearing at its upper end against an abutment 362 and at its lower end against a suitable surface formed on the treadle 300. The rod 320 passes through an opening in

the treadle and is provided with an enlarged collar so that positive depression of the rod by the roll 350 acting on the lever 324 will not positively depress the treadle but will depress it yieldingly through the spring 360. The treadle is held normally in an elevated position by the tension spring 363 which is secured at its lower end to the treadle and at its upper end to a lug on a stationary portion of the machine frame. The spring 360 provides a safety device which allows the treadle to stop at any point in its downward movement if, for example, the operator's foot should happen to be under the treadle as the latter is being forced downwardly by the rod 320.

Having thus described my invention what I claim as new and desire to secure by Letters Patent of the United States is:

1. A pad box for use in applying pressure to shoe bottoms provided with a sole receiving pad, a bracket mounted on the pad box and arranged for adjustment heightwise of the pad, a slide secured to said bracket and adjustable lengthwise of the pad, and sole and shoe positioning gages carried by said slide and constructed and arranged to position a sole and shoe relatively to each other on the pad.

2. A pad box for use in applying pressure to shoe bottoms provided with a sole receiving pad, a bracket mounted on the pad box and arranged for movement heightwise thereof, sole and shoe positioning gages carried by the bracket, said gages being arranged to rock about a horizontal axis extending transversely of the pad, and a spring for rocking the gages about said axis toward the surface of the pad.

3. A pad box for use in applying pressure to shoe bottoms provided with a sole receiving pad, a bracket mounted on one end of the pad box and arranged for movement heightwise thereof, sole and shoe gages carried by said bracket and constructed and arranged to position a sole and shoe relatively to each other on the pad, and compression springs for maintaining the bracket normally at the upper limit of its heightwise movement.

4. A pad box for use in applying pressure to shoe bottoms provided with a sole receiving pad, a bracket mounted on one end of the pad box and arranged for movement heightwise thereof, sole and shoe gages carried by said bracket and constructed and arranged to position a sole and shoe relatively to each other on the pad, compression springs for maintaining the bracket normally at the upper limit of its heightwise movement, and means for varying the amount of said heightwise movement.

5. A pad box for use in applying pressure to shoe bottoms provided with a sole receiving pad, a bracket mounted on one end of the pad box and arranged for sliding movement heightwise thereof, an adjustable stop for varying the amount of said sliding movement, a slide mounted on said bracket and adjustable lengthwise of the pad, and sole and shoe positioning fingers pivotally mounted on the slide and constructed and arranged to position a sole and shoe on the pad.

6. A pad box for use in applying pressure to shoe bottoms provided with a sole receiving pad, a bracket mounted on the heel end of the pad box and arranged for adjustment heightwise thereof, a slide carried by the bracket and adjustable lengthwise of the pad, sole and shoe positioning fingers pivotally mounted on the slide and arranged for movement about a horizontal axis extending widthwise of the pad, said fingers

being constructed and arranged to position the heel ends of a sole and shoe relative to each other on the pad, a spring for moving said fingers about said horizontal axis in a direction toward the surface of the pad, and a stop for limiting such movement, said spring acting also to permit the fingers to yield about said axis in a direction away from the surface of the pad.

7. A pad box for use in applying pressure to shoe bottoms provided with a sole receiving pad, a bracket mounted on an end of the pad box, a slide fastened to the bracket and arranged for adjustment lengthwise of the pad, a carrier member pivoted to said slide about a horizontal axis extending transversely of the pad, sole and shoe gages carried by said carrier member and arranged to position a sole and shoe relatively to each other on the pad, a spring tending to urge the carrier member about its pivot in a direction to cause the ends of the gages to approach the surface of the pad, said spring also permitting the carrier member to yield in an opposite direction, and an adjustable stop for limiting movement of the gages in a direction toward the pad.

8. A pad box for use in applying pressure to shoe bottoms provided with a sole receiving pad, a bracket mounted on an end of the pad box and arranged for movement heightwise thereof, a carrier member secured to the bracket and adjustable lengthwise of the pad, a slide pivoted to the carrier member about an axis extending widthwise of the pad, sole and shoe gages pivoted on the slide and constructed and arranged to position a sole and shoe relatively to each other on the pad, a spring for urging the carrier member in a direction to cause the ends of the gages to approach the surface of the pad, a stop for limiting such movement, and springs for permitting the bracket to yield heightwise when pressure is applied to the sole and shoe so that the gages can maintain their initial heightwise positions relatively to the sole and shoe.

9. A machine for applying pressure to shoe bottoms having, in combination, a pad box, a pad in the pad box constructed and arranged to receive a sole and shoe, means movable into position over the pad and cooperating therewith to apply pressure to a sole and shoe positioned on the pad, a bracket mounted on the pad box and movable heightwise thereof, a slide mounted on the bracket and adjustable lengthwise of the pad, a pair of gages movable toward and from each other carried by the slide, treadle controlled mechanism constructed and arranged to move the gages into engagement with the opposite edges of the sole of a shoe on the pad thereby to position the sole relatively to the pad, a second pair of gages carried by the slide and movable toward and from each other to position the shoe relatively to the sole which has been positioned on the pad, and connections controlled by the movement of the pressure applying means into operative position to operate the shoe positioning gages thereby to position the shoe relatively to the sole.

10. A machine for applying pressure to shoe bottoms having, in combination, a pad box, a sole and shoe receiving pad in the pad box, an

upwardly extending pivotally mounted frame adjacent to the pad box, means carried by said frame and movable into operative position over the pad by forward swinging movement of the frame to engage a shoe on the pad and thereafter to apply pressure to the shoe, a bracket mounted on the pad box and arranged for adjustment heightwise of the pad, a slide secured to said bracket and adjustable lengthwise of the pad, a carrier member pivoted on the slide, an abutment at one end of the carrier member for engaging the slide, a spring tending to rock the carrier member about its pivot to hold the abutment against the slide, a pair of gages on the carrier member arranged for movement toward and from each other to position a shoe on the pad, and connections between the swinging frame and the gages such that forward swinging movement of the frame brings the gages into engagement with the shoe, thereby positioning the shoe on the pad.

11. A pad box for use in applying pressure to shoe bottoms provided with a sole receiving pad, a bracket mounted on the pad box and arranged for adjustment heightwise of the pad, a slide secured to said bracket and adjustable lengthwise of the pad, a gage carrier pivoted to said slide, sole and shoe positioning gages carried by said carrier and constructed and arranged to position a sole and shoe relatively to each other on the pad, a spring tending to rock said gage carrier about its pivot in a direction to cause the sole positioning gages to approach the surface of the pad, and a stop arranged to limit the rocking movement of the gage carrier under the influence of its spring.

12. A pad box for use in applying pressure to shoe bottoms provided with a sole receiving pad, a bracket mounted on the pad box and arranged for adjustment heightwise of a shoe upon the pad, a gage carrier mounted for pivotal movement on said bracket, sole and shoe positioning gages carried by said carrier and constructed and arranged to position a sole and shoe relatively to each other on the pad, a spring tending to rock said gage carrier about its pivot in a direction to cause the sole positioning gages to approach the surface of the pad, and a stop arranged to limit the rocking movement of the gage carrier under the influence of its spring.

13. A pad box for use in applying pressure to shoe bottoms provided with a sole receiving pad, a bracket mounted on an end of the pad box and arranged for sliding movement heightwise of the pad, a spring tending to elevate the bracket, a stop limiting the upward movement of the bracket under the influence of the spring, a slide secured to said bracket and adjustable lengthwise of the pad, a gage carrier pivoted to said slide, sole and shoe positioning gages carried by said carrier and constructed and arranged to position a sole and shoe relatively to each other on the pad, a spring tending to rock said gage carrier about its pivot in a direction to cause the sole positioning gages to approach the surface of the pad, and an adjustable stop arranged to limit the rocking movement of the gage carrier under the influence of its spring.
